GRAINING COMB

Pierre P. Pastoret, 3559 Rice St., St. Paul, Minn.

Filed Sept. 10, 1956, Ser. No. 42,875

Term of patent 14 years

(Cl. D9—2)

Figure 1 is an enlarged top plan view of a graining comb, showing my design;

Figure 2 is an end view thereof taken from the bottom of Figure 1; and

Figure 3 is an enlarged bottom plan view showing of the graining comb.

The design for the graining comb disclosed resides in the arcuate end portion thereof comprising the series of graduated and outwardly diverging teeth and the V-like portions separating said teeth from the series of teeth on each side, all as shown.

I claim:

The ornamental design for a graining comb, as shown and described.
